US0D1036836S

(12) **United States Design Patent** (10) **Patent No.:** **US D1,036,836 S**
(45) **Date of Patent:** **** Jul. 30, 2024**

(54) **SHOE**

(71) Applicant: **Reebok International Limited**,
Altrincham (GB)

(72) Inventors: **Brian Christensen**, Centerville, MA
(US); **Dennis Gaboriault**, Millbury,
MA (US); **Paul Litchfield**, Westboro,
MA (US); **Ricardo Vestuti**, Providence,
RI (US)

(73) Assignee: **Reebok International Limited**,
Altrincham (GB)

(**) Term: **15 Years**

(21) Appl. No.: **29/764,868**

(22) Filed: **Jan. 4, 2021**

Related U.S. Application Data

(60) Continuation of application No. 29/671,261, filed on
Nov. 26, 2018, now Pat. No. Des. 906,655, which is
a continuation of application No. 29/592,820, filed on
Feb. 2, 2017, now Pat. No. Des. 838,452, which is a
continuation of application No. 29/508,455, filed on

(74) *Attorney, Agent, or Firm* — Sterne, Kessler,
Goldstein & Fox P.L.L.C.

(57) **CLAIM**

The ornamental design for a shoe, as shown and described.

DESCRIPTION

FIG. 1 is a perspective view of a shoe showing the claimed
design;

FIG. 2 is a right side view thereof;

FIG. 3 is a left side view thereof;

FIG. 4 is a top view thereof;

FIG. 5 is a bottom view thereof;

FIG. 6 is a front view; and,

FIG. 7 is a rear view.

The dashed broken lines in the figures show portions of the
shoe that form no part of the claimed design.

The dot-dash broken lines in the figures show boundaries
that form no part of the claimed design.

1 Claim, 6 Drawing Sheets

Related U.S. Application Data

Nov. 6, 2014, now Pat. No. Des. 779,179, which is a division of application No. 29/416,615, filed on Mar. 23, 2012, now Pat. No. Des. 719,331.
